UNITED STATES PATENT OFFICE

2,612,613

ELECTRIC DISCHARGE DEVICE

Harry C. Steiner, Scotia, N. Y., assignor to General Electric Company, a corporation of New York

Application February 25, 1950, Serial No. 146,179

6 Claims. (Cl. 313—18)

1

My invention relates to electric discharge devices and has special reference to devices of the type which employs a pool-type cathode, such as a cathode constituted of mercury.

Control electrodes, or grids as they are commonly called, have been employed in electric discharge devices having pool-type cathodes to electrostatically control the starting of the anode current in each load cycle. Single-anode devices of this type have found wide and successful use, particularly in industrial applications, as in rectification and inversion, where the very high emission capacity of the mercury pool commonly employed as the cathode meets heavy duty and short-circuit current requirements. Arc-backs are still a limiting condition in the usual installation of such devices, and hence provision must be made for rapid deionization of the arc plasma at the beginning of an inverse cycle when the device anode is negative in potential with respect to the cathode.

While the grid apertures may be made relatively small in order that a greater degree of control be exercised both during the load and inverse cycles, especially at high temperatures, the grid openings must be sufficiently large to pass the maximum currents required. Accordingly, the usual method of hastening deionization—means for cooling the arc plasma—cannot be neglected, and so, devices of this type are usually encased in a waterjacketed elongated metallic cylinder at cathode potential, which discharges the ions and condenses the cathode vapor. At the same time, it is desirable to be able to initiate the conduction cycle when the device is at low temperatures without providing preheating means or using excessive anode voltages.

Such difficulty in starting devices of this nature occurs due to lack of ionization at the low cathode vapor pressure prevailing when the tube is cold. When the ambient temperature is very low the internal vapor pressure before operation approaches that degree of vacuum associated with conventional vacuum tubes and the mean free path of the ions necessary to establish conduction is relatively long. The passage through the grid openings may be so constricted that the cathode vapor diffuses too slowly up through the grid to replenish the ion supply. Even at highly positive anode potentials relatively few electrons reach the anode, although an arc may be established between the grid and cathode spot.

This problem is amplified as the current rating, and hence the size, of the device, is increased, due to the usually longer arc path and the increased difficulty of deionization.

It is an object of my invention to provide a pool-type cathode discharge device of the nature described in which conduction may be easily established at low temperatures.

2

It is another object of my invention to provide an improved discharge device of the nature described which may be successfully operated over a wide range of vapor pressures.

5 My invention is advantageously incorporated in an electric discharge device of the type having a pool-type cathode and a deionizing metallic envelope surface surrounding the discharge path. A control electrode or grid having a bottom disk-like portion extending transversely across the discharge path is provided with a plurality of relatively large openings near the periphery of the bottom portion. Additional smaller conventional grid openings are provided in sufficient number to permit passage of the maximum required current. The large peripheral openings permit easy starting of the conduction cycle at the low vapor pressures encountered at low temperature starting without loss of control at higher operating temperatures. This advantage is due to the proximity of the arc path through the peripheral grid openings to the conducting wall or envelope surface, which quickly deionizes the nearby arc plasma of the discharge path through the large peripheral grid openings at the end of a conduction cycle. Such an arrangement does not adversely effect the maximum operating temperature and the current capacity of the discharge device and yet permits easy starting at low vapor pressures, such as commonly encountered where low ambient temperatures prevail.

30 The features which I desire to protect herein are pointed out with particularity in the appended claims. The invention itself together with further objects and advantages thereof may be best understood by reference to the following description taken in connection with the drawing in which Fig. 1 is a sectional view of a discharge device embodying my invention; Fig. 2 is a bottom view of the control electrode shown in Fig. 1; Fig. 3 is a bottom view of a modification of the grid employed in Fig. 1; and Fig. 4 is a sectional view of a portion of another discharge device embodying my invention.

35 Referring now to Fig. 1, I have shown a discharge device 1 embodying my invention in which two metal cylinders 2 and 3, so spaced as to form a water jacket between them, comprise an elongated conductive envelope for discharge device. 40 Inlet and outlet connections for cooling water are respectively placed at the bottom and top of the outer cylinder as indicated at 4 and 5. The space between the inner and outer cylinders 2 and 3 is closed at the ends of the cylinders by 45 closure rings 6 or other suitable means, and the upper and lower ends of the inner cylinder 2 are closed by transverse headers 7 and 8 which are provided with peripheral flanges hermetically 50 welded to the cylinder 2.

55 A pool-type cathode 9 is provided in the lower

end of the envelope in contact with the lower transverse header 8. This cathode may comprise a body of mercury or some other material, such as cadmium, which is capable of analogous use. A cathode current terminal is provided by a terminal block 10, secured to the underside of the lower header 8. A starting electrode 11, which, as illustrated, is of the immersion-ignitor type, is insulatingly supported from the lower header. An external terminal 12 for the starting electrode extends through the lower header 8 and is insulated therefrom. A conventional holding anode 13 is similarly insulatingly supported from the lower header with its external terminal 14 extending therethrough.

Within the envelope at its upper end is an anode 15 in the form of a graphite cylinder mounted on a rod-like conducting stem 16. A lead-in arrangement comprising a flanged metal cylinder 17, a glass sleeve 18, and a metal cap 19 serves to insulatingly support the anode and its stem from the upper head 7. An anode terminal block 20 is secured to the upper surface of the metal cap 19 and a flexible copper cable 21 is suitably connected to the terminal block to serve as a means for conducting current to the anode.

An apertured graphite control electrode or grid substantially surrounds the anode 15 to thus extend across the path of any discharge arc between the cathode 9 and the anode 15. This grid may suitably take the form of a basket having a flat bottom 23 extending transversely of the cylindrical casing and intersecting any straight-line path between the grid and anode. The grid is, of course, insulated and spaced from the anode and the envelope in order that it may function as an electrostatic control electrode, but its periphery is relatively close to the envelope where deionization time is shortest. The cylindrical side portion 24 or flange of the grid is integral with the grid bottom 23 and is connected at its upper end to the upper transverse header 7 by a plurality of cylindrical insulating bushings 25. A grid terminal bushing 26 is also connected to the grid and extends through the upper header to provide an external connection for applying the grid potential.

A splash baffle 27 is mounted above the cathode between the cathode and the face of the anode to prevent any droplets of mercury from splashing onto the grid or anode. The baffle may suitably take the form of a disk so positioned as to block any straight-line path between the active surface of the cathode and the anode.

As shown in Figs. 1 and 2, the grid is plurally perforated or apertured to allow a number of arc discharge paths therethrough in order that the initiation of the conduction cycle during each period when the anode is positive with respect to the cathode may be controlled by the grid potential. In accordance with my invention and as further shown by Fig. 2 the bottom 23 of the grid electrode is provided with a plurality of relatively large openings 28 near its periphery. These openings may suitably be circular perforations for ease of manufacture. Since the splash baffle 27 blocks any straight-line arc path between the cathode and the anode, the shortest arc paths to the anode extend around the edge of the baffle and through the large peripheral grid openings 28. Despite the relatively large size of the openings, however, arc-backs through these large grid openings are minimized due to the proximity of the grid openings to the inner casing or envelope 2, which effects rapid de-

ionization of the arc plasma after the conduction period. The deionization process is itself conventional—the device casing 2 is at cathode potential so that it discharges the ions, and it serves to cool and condense the cathode vapor.

The advantage of the large grid openings 28 is realized at low vapor pressures when the mean free path of the ions is relatively long and the arc voltage needed to produce the required ionization in conventional tubes is relatively high. Since the large openings minimize constriction of the arc path by the grid the electrons initiating conduction are able to pass through the grid openings in greater numbers to reach the anode. The cathode vapor is also able to diffuse more quickly into the region between the anode and grid and thus replenish the available ion supply. This advantage is especially significant in high current tubes of relatively large volume where the arc paths are longer. It has been observed that without the presence of the large peripheral grid openings employed according to my invention, the arc path may be so constricted that at extremely low vapor pressures there are insufficient ions to neutralize the space charge and for an instant the current is abruptly reduced as in a high vacuum discharge device with resultant voltage surges produced in the associated circuit.

In larger devices having greater volume and longer arc paths, the necessity of preventing arc constriction increases and it is likely that a substantial thickness of the grid face is required to provide mechanical strength and resistance to deterioration. Accordingly, the diameter of the peripheral grid openings should also be kept relatively large with respect to the thickness of the grid, i. e., the distance through it. This ratio should be in the neighborhood of 4:1 or greater to permit most of the electrons to pass through the grid openings on their way to the anode without striking the sides of the grid openings.

To accommodate the maximum current demand (the short-circuit duty) additional grid openings are provided. Accordingly, conventional grid openings 29 are provided in the form of a plurality of central circular holes in the grid bottom 23. When the load demand is greater than that provided by conduction through the large peripheral grid openings 28, the grid-to-cathode voltage rises and supports conduction by the longer arcs through the center openings. Were these center openings 29 also to be large as the peripheral openings, arc-backs would more frequently occur at high temperatures since the arc plasma in the center portions of the discharge device requires a greater deionization time at the end of the conducting cycle due to its distance from the cooled conductive sidewall 2.

In the embodiment of my invention shown in Figs. 1 and 2, I have also shown a plurality of grid openings 30 positioned between the central openings 29 and the large peripheral openings 28, these intermediate openings 30 also being intermediate in size. By utilizing such a graduation in size of the grid openings from the center of the grid bottom to its periphery to compensate roughly for the deionization time of the arc plasma from the center of the discharge device to its sidewalls, the operating characteristics are further improved.

A plurality of grid openings 31 are also provided in the cylindrical sidewall of the grid to increase the short-circuit capacity and also to permit greater heat dissipation from the anode

to the sidewalls of the device. These openings are adjacent the sidewalls of the tube, but their size is increasingly less important with the increase in length and voltage drop required of the arc paths through them. Accordingly, while the size of the openings 31 could be variously regulated, I have not found it necessary to do so since grid openings in the bottom face of the grid accommodate the arcs for starting conduction.

Fig. 3 shows a modification of the bottom face 32 of a grid corresponding to the grid 22 shown in Fig. 1. A plurality of large peripheral grid openings 33 are provided to permit starting at low vapor pressures as previously discussed. The central portion of the grid bottom is left imperforate, but the openings 33 are roughly triangular in shape with an apex of the triangle extending towards the center of the grid bottom so that greater electrostatic control may be exerted at this apex, while the larger and more open portion of the grid opening is nearest the periphery where the deionization time is less. Various configurations and combinations of larger and smaller openings may be employed without departing from the spirit of my invention, depending upon the requirements of the device as to minimum vapor pressure and current requirements.

In Fig. 4, I have shown my invention as embodied in a single anode, multi-grid discharge device of the type having a pool-type cathode. In this device, the anode 35 is surrounded by a successive plurality of grids; in this case, an inner grid 36, an intermediate grid 37, and an outer grid 38. The envelope 39 of the device is preferably a double-walled metallic cylinder of the type shown in Fig. 1 and which acts in the same manner to deionize the arc plasma at the end of each conduction cycle. Each of the grids is provided with a plurality of central openings 40 which operate in a conventional manner. In accordance with my invention, a plurality of larger peripheral or near peripheral openings 41, which function as to the large openings 28 shown and described for Figs. 1 and 2, is provided in the bottom portion of each grid. While those portions of the arc path defined by the large peripheral openings in the inner and intermediate grids 36 and 37 are not subject to such rapid deionization as are the arc path portions at the peripheral openings in the outer grid 38, the inner and intermediate peripheral grid openings should also be relatively large in order not to constrict the arc paths and cancel the advantages obtained by utilizing the large peripheral openings in the outer grid. The large peripheral openings in the respective grids are preferably aligned so far as practical to further decrease arc constriction and permit electrons to reach the anode to begin each conduction cycle. Since without the large openings near the grid bottom peripheries the minimum vapor pressure at which conduction could start would be relatively high, due to the constriction of the arc paths caused by the plurality of grids, my invention is very advantageously employed in multi-grid devices of this nature.

For the purpose of this application, I have used the terms grid and control electrode synonomously and intend that they be so interpreted.

While the present invention has been described by reference to particular embodiments thereof, it will be understood that numerous

modifications may be made by those skilled in the art without departing from the invention. I, therefore, aim in the appended claims to cover all such equivalent variations as come within the true spirit and scope of the foregoing disclosure.

What I claim as new and desire to secure by Letters Patent of the United States is:

1. An electric discharge device comprising a single main anode and a pool-type cathode spaced from the anode to provide discharge paths for conduction therebetween, means for deionizing the space defining said discharge paths after conduction comprising metal wall surfaces laterally surrounding said discharge path, said wall surfaces being in conductive relationship with said cathode, and means for controlling the initiation of conduction comprising a control electrode having a face extending across said discharge path with its periphery near said wall surfaces, said face being provided with a plurality of openings to define discharge paths therethrough, said openings near the periphery of said surface being substantially larger than those near its center in order to facilitate initiation of conduction in paths near said deionizing means.
2. An electric discharge device comprising a single main anode and a pool-type cathode spaced from the anode, deionizing means comprising metal wall surfaces laterally surrounding the discharge path between the anode and the cathode, said metal wall surfaces being in conductive relationship with said cathode, and a control grid having a face extending transversely across said discharge path with its periphery near said wall surfaces, said face of said grid having a plurality of perforations to provide arc passages therethrough, the perforations near the periphery of said face being substantially larger than the perforations near the center of said face in order to facilitate initiation of conduction in paths near said deionizing means.
3. An electric discharge device comprising a single main anode and a pool-type cathode spaced from the anode, deionizing means comprising metal wall surfaces laterally surrounding the discharge path between the anode and the cathode, said metal wall surfaces being in conductive relationship with said cathode, and a control grid having a face extending transversely across said discharge path with its periphery near said wall surfaces, said face of said grid having a plurality of perforations to provide arc passages therethrough, the perforations being progressively smaller from the periphery of said face to its center in order to facilitate initiation of conduction near said deionizing means.
4. An electric discharge device comprising a single main anode and a pool-type cathode spaced from the anode, deionizing means comprising metal wall surfaces laterally surrounding the discharge path between the anode and the cathode, said metal wall surfaces being in conductive relationship with said cathode, and a control grid having a face extending transversely across said discharge path with its periphery near said wall surfaces, said face of said grid having a plurality of large openings near said periphery to provide arc passages therethrough, and relatively the center portion of said face being imperforate in order to facilitate initiation of conduction near said deionizing means.
5. In an electric discharge device employing

mercury as an ionizable medium and comprising a generally cylindrical elongated metal envelope and an anode and cathode within the envelope at opposite ends thereof, a control electrode interposed in the discharge path between said anode and said cathode, said electrode having a disk-like portion extending transversely of said envelope with its periphery near said envelope, said portion having a plurality of apertures with at least one of said apertures near 10 its periphery being substantially larger than apertures nearer the center of said portion.

6. An electric discharge device comprising a single main anode and a mercury pool-type cathode spaced from the anode, an elongated 15 metal envelope laterally surrounding the space comprising a discharge path between said anode and said cathode, said envelope being in conductive relationship with said cathode, means for cooling said envelope to facilitate deionization 20 of said space, and a control electrode having a

plurality of perforated disk-like graphite portion extending transversely of said discharge path with its periphery near said envelope, said portion having relatively large perforations near its periphery, the diameters of said perforations being at least four times the thickness of said disk-like portion, and having substantially smaller perforations near its center portion.
